Primary Examiner — Ricky Pham*(74) Attorney, Agent, or Firm* — Edward S. Sherman**CLAIM**

The ornamental design for a round lid for a storage container, substantially as shown and described.

DESCRIPTION

FIG. 1 is a top perspective view of the “round lid for a storage container”, showing my new design;

FIG. 2 is a bottom perspective view thereof;

FIG. 3 is a top plan view thereof;

FIG. 4 is a bottom plan view thereof;

FIG. 5 is a side elevation view thereof; and,

FIG. 6 is a cross sectional elevation view thereof that is taken at section line 6-6 in FIG. 3.

The broken lines in the drawings represent unclaimed portions of the design.

1 Claim, 5 Drawing Sheets See application file for complete search history.
